(57) **CLAIM**

The ornamental design for a power tap with low voltage cordless capability, as shown and described.

DESCRIPTION

FIG. 1 is a front perspective view of the power tap with low voltage cordless capability showing our new design mounted in an operating environment and with its door shown in a closed position;

FIG. 2 is another front perspective view of the power tap with low voltage cordless capability of FIG. 1, shown in the operating environment and with its door shown in an open position;

FIG. 3 is a rear perspective view of the power tap with low voltage cordless capability of FIG. 2;

FIG. 4 is a front perspective view of the power tap with low voltage cordless capability of FIG. 2;

FIG. 5 is a rear elevation of the power tap with low voltage cordless capability of FIG. 2;

FIG. 6 is a front elevation of the power tap with low voltage cordless capability of FIG. 2;

FIG. 7 is a left side elevation of the power tap with low voltage cordless capability of FIG. 2;

FIG. 8 is a right side elevation of the power tap with low voltage cordless capability of FIG. 2;

FIG. 9 is a top plan view of the power tap with low voltage cordless capability of FIG. 2;

FIG. 10 is a rear elevation of the power tap with low voltage cordless capability of FIG. 1;

FIG. 11 is a front elevation of the power tap with low voltage cordless capability of FIG. 1;

FIG. 12 is a left side elevation of the power tap with low voltage cordless capability of FIG. 1;

FIG. 13 is a right side elevation of the power tap with low voltage cordless capability of FIG. 1;

FIG. 14 is a top plan view of the power tap with low voltage cordless capability of FIG. 1; and,

FIG. 15 is a front perspective view of the power tap with low voltage cordless capability of FIG. 1.

The broken lines are included for the purpose of illustrating portions of the power tap with low voltage cordless capability that form no part of the claimed design.
